CLAIM

What is claimed is the ornamental design for a ballistic protective element, as shown and described.

DESCRIPTION

FIG. 1 is a side view of the ballistic protective element;

FIG. 2 is an isometric view thereof;

FIG. 3 is a top view;

FIG. 4 is another side view;

FIG. 5 is a bottom view; and,

FIG. 6 is a view from an edge thereof.

1 Claim, 1 Drawing Sheet**FIG. 1**

FIG. 2

FIG. 3

FIG. 4

FIG. 5

FIG. 6

UNITED STATES PATENT AND TRADEMARK OFFICE
CERTIFICATE OF CORRECTION

PATENT NO. : Des. 566,340 S
APPLICATION NO. : 29/237697
DATED : April 8, 2008
INVENTOR(S) : Benyami et al.
